UNITED STATES PATENT OFFICE.

SILAS H. HAMILTON, OF LAWRENCE, KANSAS, ASSIGNOR, BY MESNE ASSIGNMENTS, TO MARVIN A. FARR, OF CHICAGO, ILLINOIS.

APPARATUS FOR MANUFACTURING BUILDING-BOARD FROM PAPER.

SPECIFICATION forming part of Letters Patent No. 269,786, dated December 26, 1882.

Application filed April 5, 1881. Renewed October 24, 1881. (No model.)

To all whom it may concern:

Be it known that I, SILAS H. HAMILTON, of Lawrence, in the county of Douglas, and in the State of Kansas, have invented certain new and useful Improvements in Apparatus for Manufacturing Building-Board from Paper; and I do hereby declare that the following is a full, clear, and exact description thereof, reference being had to the accompanying drawings, making a part of this specification, in which—

Figure 1 is a side elevation of my improved machinery. Fig. 2 is an enlarged front elevation of the mechanism used for cutting in lengths the completed board, and Fig. 3 is an enlarged side elevation of the journal-bearing of one end of a pair of pressure-rollers.

Letters of like name and kind refer to like parts in each of the figures.

20 The object of my invention is to enable building-boards to be produced at one operation from paper; and to this end it consists principally in the means employed for saturating sheets of paper with waterproofing composition, substantially as and for the purpose hereinafter specified.

It consists, further, in the means employed for applying an adhesive mixture to the sheets of paper, substantially as and for the purpose 30 hereinafter shown.

It consists, further, in the means employed for combining sheets of adhesive coated paper and forming the same into a board, substantially as and for the purpose hereinafter set forth.

35 It consists, further, in the means employed for adjusting to and securing in relative position the pressure-rollers of each pair, substantially as and for the purpose hereinafter shown and described.

It consists, further, in the means employed for cutting in lengths the completed board, substantially as and for the purpose hereinafter specified.

45 It consists, finally, in the combination and arrangement of the various parts of the machine, substantially as and for the purpose hereinafter shown.

50 My mechanism is intended for use in the carrying out of my method of manufacturing building-board from paper, in which several

strips or sheets of such material are first simultaneously passed through a waterproofing mixture, are next dried and then coated upon one side each with an adhesive mixture, are 55 next subjected to a heavy pressure to cause them to adhere together in the form of a board, which is finally severed into suitable lengths. In carrying into effect such method the paper A is formed in long strips, a number of which, 60 in the form of rolls, are supported upon a suitable rack, B, in such position as to enable each strip to be unrolled and drawn out without interference from other strips. From the frame B each strip of paper A passes horizontally to and over a roller, C, thence downward around a second roller, D, thence forward around a third roller, E, and thence upward over a fourth roller, F, which said rollers, in connection with similar rollers for each 70 strip of paper to be operated upon, are journaled in the order shown in Fig. 1 upon a frame, G, that is placed over a vat, H, and is capable of being raised above the same, or of being lowered until the bottom rollers, C and 75 D, with their strips of paper, are below the upper edge of said vat. The vat H is intended to contain a waterproofing mixture, and is provided with steam or other suitable means for imparting to its contents any required degree of temperature. From the rollers F the paper A passes horizontally a sufficient distance to cause each strip to become thoroughly dry, during which transit said strips pass over and are supported by means of frames of slats 85 or rollers I, that are arranged at suitable distances from each other. The strips of paper A from the frames I next pass severally through or over a series of vats, K, each of which vats contains an adhesive mixture, and is supplied 90 with a brush-roller, k, that is journaled in such position as to cause its lower side to dip into said adhesive mixture while its upper side is in contact with the lower face of one of said strips. Said rollers are caused to rotate, 95 and as said paper advances transfer to the lower face of each sheet a portion of the said mixture.

In order that contact between the paper A and brush-roller k may be insured, a roller, k', 100 is placed at each edge, front, and rear of the vat K, beneath which the said paper passes,

while, in order that all surplus adhesive mixture may be removed from said paper, a scraper, k^2 , is arranged in such position near the edge of said vat as to come into contact with the latter after it leaves said brush and before passing from said vat. From the vat K the strips of paper are brought together between two rollers, L, and from thence pass horizontally between a series of metal rollers, M, which are arranged in pairs, that are geared together and the different pairs connected by gearing, so that said rollers shall simultaneously rotate with their impinging peripheries moving in a forward direction.

15 The rollers M are heated by means of steam or in any well-known manner, and, being arranged to impart great pressure to the paper passing between, cause the strips A to adhere firmly together and produce from the same a board having great density. The relative positions of the rollers M of each pair are insured by means of a screw, m, which is placed between the journal-boxes m' , at each end of the same, and is arranged so that by turning 20 said screw in one direction said boxes are drawn toward each other and by turning it in an opposite direction they are moved apart. A screw, m^2 , placed above the upper box of each set enables said box to be held firmly 25 down to place when adjusted thereto.

30 As the board is formed it is cut into suitable lengths by means of a device shown in Fig. 2, which consists of a knife or cutter, N, which is suspended from a suitable frame, P, by means 35 of two hangers, O, above and at a right angle to the board to be cut, the arrangement being such as to enable said cutter to swing longitudinally to one side, so as to raise its edge above said board, as shown by the full lines of 40 Fig. 2, and by moving in an opposite direction to assume the position shown by dotted lines of same figure, with its said cutting-edge below the lower face of said board.

The cutter N is held in its elevated position 45 by means of springs n, placed beneath its ends, and is moved laterally downward by two cams, Q, which are pivoted upon the frame P, and by means of radial arms q and a connecting-bar, q' , are combined so as to move simultaneously. As thus arranged, it will be seen 50 that the cutter N impinges upon the board with

a drawing cut, which causes a clean division of the same and prevents waste.

Having thus fully set forth the nature and merits of my invention, what I claim as new 55 is—

1. The means employed for saturating sheets of paper with a water-proof mixture, consisting of a frame of rollers, substantially as described, around which said paper passes, made 60 vertically adjustable within a vat, substantially as and for the purpose specified.

2. As a means for applying an adhesive mixture to the strips of paper, the vat K, provided with the brush-roller k, guiding-rollers k' , and 65 scraper k^2 , combined to operate substantially as and for the purpose shown.

3. As a means for combining the sheets of adhesive coated paper, the pressure-rollers M, arranged in pairs and heated and combined 70 to move simultaneously, substantially as set forth.

4. In combination with the journal-boxes m' of the rollers M, the screw m, interposed between the same, and the screw m^2 , arranged to 75 impinge upon the upper of said boxes, substantially as and for the purpose shown and described.

5. As a means for cutting into lengths the completed board, the cutter N, arranged to 80 swing longitudinally in a vertical plane and caused to impinge upon said board with a drawing cut by mechanism substantially as described, substantially as and for the purpose specified.

6. As a means for making board from paper, the roll-supporting frame B, the rollers C, D, E, and F, journaled within the vertically-adjustable frame G over or within the vat H, the supporting-frames I, the adhesive-mix- 85 ture vats K, provided with the brush-roller k, guiding-rollers k' , and scraper k^2 , and the pressure-rollers M, said parts being combined to operate in the manner and for the purpose substantially as shown.

In testimony that I claim the foregoing I have hereunto set my hand this 4th day of April, 1881.

SILAS H. HAMILTON.
